UNITED STATES PATENT OFFICE

CLINTON H. HAVILL, OF SOUTH ORANGE, NEW JERSEY, ASSIGNOR TO BENDIX RESEARCH CORPORATION, OF EAST ORANGE, NEW JERSEY, A CORPORATION OF INDIANA

PROPELLER

Application filed May 20, 1931. Serial No. 538,801.

This invention relates to propellers, and more particularly to propellers of the hollow metal type.

Heretofore, there have been proposed hollow metal propeller blades which possess several advantages over wooden propeller blades, among which may be mentioned durability, rigidity, and increased strength, such factors rendering this type of propeller blade especially adaptable for use on aircraft. In all prior constructions of hollow metal propeller blades, however, extreme difficulty has been experienced in forming the inner end or root of the blade in such a manner as to adapt the same for reception by the usual hub, and at the same time to impart sufficient strength and rigidity to the blade root to successfully withstand the enormous forces to which the same is subjected during operation of a propeller embodying this type of blade.

It is accordingly one of the objects of the present invention to provide a hollow metal propeller so constructed as to obviate the above difficulties.

Another object of the invention is to provide a novel propeller blade construction of the built-up type having a separately formed root or hub portion.

Still another object is to provide in a hollow propeller blade construction, a novel, separate, integrally-formed root member adapted to be secured to a plurality of blade members whereby an exceedingly strong and durable propeller blade is effected.

A further object is to provide a novel blade root or hub member for a propeller blade, having a plurality of integrally-formed outwardly extending arms adapted to constitute a portion of the edges of the blade and to which a plurality of blade members are adapted to be secured, whereby an exceedingly strong and efficient propeller blade may be produced at minimum cost.

Other objects and novel features of the invention will appear more fully hereinafter from the following detailed description when taken in connection with the accompanying drawing. It is to be expressly

understood, however, that the drawing is for purposes of illustration only and is not designed as a definition of the limits of the invention, reference being had for this purpose to the appended claims.

Referring to the drawing, wherein like reference characters refer to like parts throughout the several views:

Fig. 1 is a plan view of a blade root member embodying the present invention;

Figs. 2, 3, 4, 5, 6, and 7 are axially spaced transverse sections of the root member shown in Fig. 1;

Fig. 8 is a plan view of a finished blade embodying the root member shown in Fig. 1, a portion of said member being illustrated in section; and

Figs. 9, 10, 11, 12, and 13 are transverse sections of the finished blade.

Referring more particularly to Figs. 1-7, a blade root member constructed in accordance with the present invention is illustrated therein as constituted by a substantially cylindrical inner end or hub portion 14 which has preferably formed integrally therewith an annular flange or shoulder 15 adapted to fit within the socket of the usual propeller hub. Adjacent the other end of the hub portion 14, the blade root member is formed with a pair of outwardly extending divergent arms 16 and 17 for a purpose which will appear more fully hereinafter. Preferably, the blade root member is formed in one piece, as by forging, and in order to provide a light weight construction, the member is hollow, as indicated on the drawing.

As will be observed from Figs. 3-7, each of the arms 16 and 17 is gradually tapered from one end to the other and is provided on either side thereof with ledges 18 and 19 which are adapted to receive the inner ends of a pair of blade members 20 and 21, these last named members being secured in said ledges by any suitable means, as for example, by welding.

Preferably, each of the blade members 20 and 21 is reinforced by laminations 22 and 23 respectively, and these laminations may be secured to the blade members under tension, if desired, in order to relieve the outer faces

of the finished blade of a portion of the tension load imposed thereon by reason of the centrifugal force developed during operation of a propeller embodying blades constructed in this manner.

In assembling the laminated blade members with respect to the root member, the blade members 20 and 21, to which the laminations 22 and 23 are secured, are marginally secured together adjacent their meeting edges, as by welding, and the inner spaced apart ends of said blade members are fitted in the ledges 18 and 19 and suitably secured therein. It will be observed from Figs. 9 and 10 that the aforementioned ledges are of sufficient depth to cause the outer surfaces of the blade members to fit flush with the outer surfaces of the arms 16 and 17 in order to produce a smooth blade contour. If desired, the blade may thereafter be placed within a suitable die after proper heating, and a fluid under pressure may be inserted within the blade in order to expand the same and force the exterior surface thereof into intimate contact with the surfaces of the die, to effect the blade shape desired. The blade thus formed may be thereafter burnished and polished in a manner well known to those skilled in the art.

There is thus provided by the present invention a novel propeller blade constructed of the built-up hollow metal type embodying a separately formed root member. By forming the inner end portion or root of the blade as a separate member, an unusually strong and durable structure is secured. The provision of the outwardly extending arms on the root portion serves not only to effect a firm and secure anchorage for the inner end portions of the blade members, but also forms a portion of the leading and trailing edges of the finished blade, and thus reinforces these portions which are subject to tremendous bending and twisting forces during operation. Such construction also eliminates all marginal welds or seams adjacent the inner end of the propeller blade which might have a tendency to open during operation.

Though only one embodiment of the invention has been illustrated and described, it is to be expressly understood that the same is not limited thereto but may be embodied in various forms. For example, more than two blade-supporting arms may be provided for the root member and more than one lamination may be employed with each blade member, if desired. It is also to be understood that the inner ends of the blades of the hub member may be secured in the ledges of the hub member by means other than welding, as for example, by means of rivets. Other changes may be made in the relative sizes, shapes and locations of the component parts of the invention, as will now be understood by those skilled in the art, without departing from the

spirit thereof. Reference will, therefore, be had to the following claims for a definition of the limits of the invention.

What is claimed is:

1. A built-up metal propeller blade having a separately formed root member, said member having a substantially cylindrical hub portion, a pair of oppositely disposed divergent arms integrally formed with respect to said hub portion, a ledge disposed on either side of said arms, and a pair of laminated blade members secured together at their outer extremities and secured at their inner extremities in said ledges. 70

2. A hollow metal propeller blade comprising a separately formed root member, said member having a cylindrical hub portion and a pair of outwardly extending arms, a pair of blade members marginally secured together at their outer end portions, and means for securing said blade member to said arms at the inner end portions of said members. 80

3. A metal propeller blade comprising a hollow root member having a pair of longitudinally extending arms adapted to constitute a portion of the leading and trailing edges of the blade, and blade members secured to adjacent portions of each of said arms and to each other to form a hollow 90 metal blade. 95

4. A metal propeller blade comprising a hollow root member having a pair of oppositely disposed divergent arms, each of said arms being provided with ledges, and blade members secured in said ledges and to each other to form a hollow propeller blade. 100

5. In a metal propeller blade, a separately formed root member having a substantially cylindrical end portion, and a pair of outwardly extending arms integral therewith, each of said arms being provided with a ledge on either side and disposed inwardly of the marginal portion thereof. 105

6. In a metal propeller blade, a separately formed root member having a substantially cylindrical hub portion, a pair of longitudinally extending arms integrally formed with said hub portion and gradually tapering outwardly, each of said arms being provided with ledges on either side thereof and adapted to receive the inner ends of a pair of blade members. 110

7. A blade root member for a propeller blade comprising a substantially cylindrical 120 end portion, a pair of longitudinally extending arms adapted to constitute a portion of the leading and trailing edges of the blade, said arms being formed integrally with said cylindrical end portion, and means formed 125 on each of said arms for receiving a pair of blade members.

8. A propeller blade comprising a hollow, forged root member having a substantially cylindrical end portion, a plurality of out- 130

wardly tapering arms integrally formed therewith, a plurality of blade members, a ledge provided on either side of said arms for receiving the inner ends of said blade members, said members being marginally secured together adjacent the outer ends thereof to form with said root member, a hollow propeller blade.

9. A propeller blade comprising a separately formed root member having a substantially cylindrical end portion, a plurality of outwardly extending supporting members formed integrally with said hub portion, said members forming a portion of the leading and trailing edges of the blade, and a plurality of blade members secured to each other and to said supporting members.

10. A propeller blade comprising a separately formed hollow root member having a substantially cylindrical end portion, a pair of outwardly extending divergent arms formed integrally with said end portion, said arms forming a portion of the leading and trailing edges of the blade, a ledge formed on either side of each of said arms and disposed inwardly of the marginal portion thereof, and a pair of blade members secured together adjacent their outer end portions and welded in said ledges adjacent their inner end portions to form with said root member a hollow propeller blade.

11. A propeller blade comprising a separately formed root member having a pair of outwardly extending arms adapted to form portions of the leading and trailing edges of the blade respectively, said arms being adapted to be secured to a pair of blade members for completing the blade.

In testimony whereof I have signed this specification.

CLINTON H. HAVILL.
